UNITED STATES PATENT OFFICE.

ROBERT H. DOWLING, OF NEWARK, OHIO, ASSIGNOR OF ONE-HALF TO
BENJAMIN B. LOAR, OF SAME PLACE.

WHISTLE FOR CABINET AND PIPE ORGANS.

SPECIFICATION forming part of Letters Patent No. 249,322, dated November 8, 1881.

Application filed May 3, 1881. (Model.)

To all whom it may concern:

Be it known that I, ROBERT H. DOWLING, of Newark, in the county of Licking and State of Ohio, have invented certain new and useful 5 Improvements in Whistles for Cabinet and for Pipe Organs; and I do hereby declare the following to be a full, clear, and exact description of the invention, such as will enable others skilled in the art to which it appertains to make 10 and use it, reference being had to the accompanying drawings, which form part of this specification.

My invention relates to improvements in whistles for cabinet and for pipe organs. 15 The object of my invention is to do away with the hissing sound in pipe-organs resulting from the pressure in any great degree upon the bellows, and also to do away with the blowing-bellows in cabinet or reed organs, by 20 substituting in a pipe-organ a whistle or pipe, the musical sound of which is produced by an exhaust-bellows, and substituting in cabinet-organs a like whistle, the sound being produced by the suction-bellows. The tone resulting 25 from this suction-whistle is much smoother and will blend more harmoniously than that arising from the blow-whistle now in use.

My whistle or pipe herein described may be constructed of any metal or material, and may 30 be either round or square in form.

Figure 1 represents my invention as applied to pipe-organs. Fig. 2 is a sectional view of my invention as applied to cabinet-organs. Fig. 4 is a sectional view of my invention. 35 Fig. 3 is a view of under side of part B. Fig. 5 is an inside view of A. Fig. 6 is a view of A at the end opposite to which suction is applied. Fig. 7 is a view of B at that end which forms a tongue, the tongue being formed by 40 B being beveled, as shown in Fig. 4.

It will be seen that A, Figs. 5 and 6, is rabbed or channeled on the inside face, and that part B has a beveled tongue upon the under

side. The upper face of B is smooth. The pieces A and B are of the same width, and 45 when said two pieces are placed together there is an air chamber or passage formed—viz., by said channel or rabbet in A, the tongue upon B being underneath and at the end opposite to which suction is applied. Suction is applied 50 at that part marked E.

C, Fig. 1, is the pipe, to which my invention is attached in pipe-organs by closing the end of the pipe to which the whistle is to be attached, leaving a small opening in the side of 55 the pipe, as indicated by the dark lines in C, Fig. 1. Over this opening rests the beveled tongue at the end of B, leaving still a small part of the opening in the pipe uncovered, as seen by reference to Fig. 2.

In cabinet or reed organs my invention is attached to the end of the pipe in the manner indicated in Fig. 2.

The tone is regulated the same as the tone of pipe-organs and whistles in cabinet or reed organs is now regulated—viz., by the tuning-slide D sliding in the pipe C, as shown in Figs. 1 and 2, and therefore I do not claim such method of tuning as part of my invention; but

What I do claim, and desire to secure by 70 Letters Patent, is—

An organ-whistle having a mouth-piece consisting of the channeled piece A, in combination with the piece B, having the beveled tongue, and arranged at the side or end of the pipe in 75 the manner described above, whereby the pipe is adapted to produce tones by having the air drawn through it by an exhaust-bellows.

In testimony whereof I have hereunto subscribed my name in the presence of two witnesses.

ROBERT H. DOWLING.

Witnesses:

JAMES B. THOMAS,
HENRY MOORE.
